APPARATUS FOR WORKING ARTICLES

Cecil C. McCain, Glen Ellyn, Ill., assignor to
Western Electric Company, Incorporated, New
York, N. Y., a corporation of New York

Application August 6, 1943, Serial No. 497,636

11 Claims. (Cl. 51—3)

This invention relates to an apparatus for working articles and more particularly to an apparatus for slabbing and lapping quartz crystals.

In one stage in the manufacture of quartz crystals for use as frequency control devices in certain types of electronic communication equipment, it is sometimes the practice to cut the rough quartz blocks into slabs. The cutting operation, which may be performed with a diamond edged saw, may leave a roughened surface on the crystal slab which renders difficult optical inspection of the slab to determine the axes or other desired characteristics of the crystal and it is, therefore, usually necessary to lap one side of each slab in order to obtain a suitable plane surface.

Objects of the present invention are to provide an efficient and effective apparatus for slabbing and lapping quartz crystals.

In accordance with one embodiment of this invention, an apparatus may be provided for slabbing and lapping quartz crystals in which a circular saw is rotatably mounted on an arm which is, in turn, mounted on a clutch-driven shaft which is rotatable to engage the saw with the quartz block. A lapping disc is also rotatably mounted on an arm which is mounted on the clutch-driven shaft and after the saw has cut through the crystal block, the disc is moved into engagement with the cut face of the block to lap the surface thereof.

Other objects and advantages of the present invention will be more apparent from the following detailed description taken in conjunction with the drawings, wherein

Fig. 1 is a front elevation of a slabbing apparatus constructed in accordance with this invention;

Fig. 2 is a plan view of the same apparatus, partly in section;

Fig. 3 is an end elevation of the same apparatus;

Fig. 4 is an enlarged, vertical, sectional view along the line 4—4 of Fig. 3; and

Fig. 5 is a vertical, sectional view along the line 5—5 of Fig. 4.

One practice in preparing quartz crystal slabs has been to cut a rough crystal into slabs and then to transfer the slabs to a lapping apparatus wherein the slabs are ground to obtain suitable surfaces for inspection. Transferring the crystal slabs from one apparatus to another involves removing the slabs from the cutting apparatus and then carefully positioning the slabs in the lapping apparatus. Because of the high degree of accuracy required for crystals to be used as frequency control devices, the positioning and align-

ing of the crystal slab in both the cutting and the lapping operations must be done with great care. By eliminating one positioning operation, a considerable reduction may be effected in the cost of preparing such crystals.

In accordance with the present invention, both the cutting and the lapping operations are successively performed in the same apparatus, thus eliminating the step of transferring the crystal slabs to a lapping apparatus and, as aforesaid, substantially reducing the operational cost. Referring to the drawings, and particularly to Fig. 1, an apparatus for performing both the slabbing and lapping operations is there illustrated comprising a base 10 on which are mounted two vertically disposed, spaced standards 11 and 12. A bracket arm 13 is integrally formed with the right standard 12 and extends a short distance to the right thereof, as shown in Fig. 1. Bearings 15 and 16, respectively, are formed in the upper ends of the standards 11 and 12, and a shaft 17 which extends between these standards is rotatably journaled in these bearings.

A sleeve 18 is mounted on the shaft 17 and is keyed thereto by a pin 19, which extends transversely through both the sleeve and the shaft. This sleeve serves as a rotatable support for a pair of arms 22 and 23 which are rigidly fixed to the left portion thereof and which extend radially therefrom at substantially right angles to each other, as shown in Fig. 3. The outer ends of both of the arms 22 and 23 are provided with elongated bearings 24 and 25, respectively, in which are journaled shafts 26 and 27, respectively. The shaft 26 serves as a rotatable support for a circular saw 30 which is fixed to the right end thereof, while the shaft 27 serves as a rotatable support for a lapping disc 31, also fixed to the right end thereof.

The lapping disc and the saw are rotated by a common belt 32, which passes over pulleys 33 and 34 connected to the left ends of shafts 26 and 27, respectively, and which is driven from a double pulley 35 rotatably mounted on the shaft 17. A second belt 36 drives the double pulley 35 and may be connected to any suitable power source (not shown). It will be apparent from the foregoing that regardless of the relative angular position of the sleeve 18, the saw and lapping disc may be rotated on their respective shafts by the belt 32.

In sawing quartz crystals, it may be desirable to provide a certain maximum cutting pressure in order to prevent damage to either the crystal block or to the cutting tool. In the present ap-

paratus, the cutting pressure is controlled by a spring clutch designated generally at 40. A clutch plate 41 is fixed to the right end of the shaft 17 which extends a short distance beyond the bearing 18, the clutch plate being fixed to the shaft 17 by a set screw 42. Immediately adjacent the clutch plate 41 and engageable therewith in driving relationship is a second clutch plate 43 which is mounted on a short stud shaft 44, and fixed thereto by a set screw 45. The right end of the shaft 44 is journaled in a bearing 46 integrally formed with the upper end of the bracket arm 13, the stud shaft being axially slideable therein as well as rotatable. A pilot pin 47 extends from the center or axis of the shaft 17 into a cylindrical recess 48 formed in the left end of the stud shaft 44 and provides an auxiliary support for the stud shaft and associated parts.

The stud shaft 44 is driven by a pulley 50 which is fixed to the right end thereof and around which passes a belt 51 which may be driven by any suitable means (not shown) to obtain a maximum speed of rotation of approximately 12 R. P. M. The clutch plate 43 is normally engaged in driving relationship with the clutch plate 41 by a helically coiled spring 52 which is positioned about the stud shaft 44, one end of the spring bearing against the left side of the bearing 46 while the opposite end of the spring bears against the rear of the clutch plate 43. The spring 52 is selected to provide a contact pressure between the clutch plates which will permit them to slip when a certain predetermined maximum resistance to rotation is encountered.

When it is desired to disengage the clutch plate 43 from the clutch plate 41 to prevent the rotation of the sleeve 18, a ring 55, which is positioned between the pulley 50 and the bearing 46, being mounted on the stud shaft 44 and freely rotatable with respect thereto, is rotated with respect to the bearing 46 to move the clutch plate 43 to the right. This is accomplished by a camming projection 56, which then is moved out of a notch 57 formed in the right side of the bearing 46 and forces the pulley 50 and associated shaft 44 to the right, thus disengaging the clutch plate 43 from the plate 41. A handle 58 is attached to the ring 55 to facilitate the operation thereof and a stop member 59 mounted on the bearing 46 limits the rotation of the ring 55.

In using this apparatus, a block 60 of quartz is cemented to a supporting plate 61 of glass, or other relatively easily cut material having sufficient rigidity to serve as a support for the crystal block during the slabbing and lapping operations, and the plate is transferred to a platform 62, suitably positioned adjacent the saw and disc, as shown. This platform is pivotally supported on a bolt 63 which is mounted on a bifurcated upper portion 64 of a vertically disposed support 65, the base of which is mounted on a base 10 of the apparatus. The platform 62 may thus be adjusted so that the saw 39 may cut the crystal block 60 over a range of angles thereto of substantially more than 90°. When the platform has been adjusted to the desired position, a nut 66, threaded to the right end of the bolt 63, as shown in Fig. 5, is tightened to lock the platform in adjusted position.

As may be seen in Figs. 4 and 5, when the plate 61 with the block of quartz cemented to the upper side thereof is placed on the platform 62, the forward portion of the plate rests on a pair of parallel, spaced ways 70 integrally formed with the upper surface of the platform 62 and extend-

ing substantially the length thereof. The rear of the plate 61 then rests on three parallel spaced blocks 71, 72 and 73, which are slidably mounted on the upper surface of the platform 62 and which are rigidly joined by a cross plate 74. As shown in Fig. 5, the two side edges of the platform 62 are raised to form longitudinally extending flanges 75 and the two side blocks 71 and 73 are slidably positioned in the spaces between the ways 70 and the flanges 75. It will be noted that the inner sides of the flanges 75 are bevelled outwardly to receive dovetail portions 76 and 77, respectively, of the blocks 71 and 73. These dovetail portions aid in maintaining correct alignment of the supporting plate 61 with respect to the platform 62.

The center block 72 is positioned in a semi-cylindrical recess 89 positioned in the center portion of the platform 62 and extending longitudinally therethrough. This block 72 is provided with a longitudinally extending aperture 84 which is internally threaded to receive and engage a threaded rod 82, which is journaled in a supporting block 83, rigidly mounted on the rear of platform 62. A collar 84 integrally formed with the rod 82 bears against the left side of the block 83 while a large knurled nut 85, fixed to the right end of the rod 82, bears against the left side of the block 83, thus holding the shaft in position as well as providing a suitable means for manually rotating the shaft.

After the quartz block and supporting plate 61 have been positioned on the platform 62, as has been described, a clamping plate 86 is placed over the rear portion of the plate 61 and bolted to the slidably mounted blocks 71 and 73. This clamping plate is preferably made of a relatively resilient material, such as a fibrous material impregnated with a phenolic condensation product, so that, while it may exert considerable clamping force, it will not crush the plate 61, which may be, as aforesaid, made of glass. It will, thus, be apparent that by rotating the threaded rod 82, the quartz block may be moved relatively to the platform 62. A micrometer collar 88 is positioned about the knurled nut 85 and facilitates determination of the amount that the quartz block is advanced by a given rotation of the rod 82.

In operating this apparatus, after the quartz block has been positioned on the platform, as described, the sleeve 18 is rotated by engaging the clutch plate 43 with the clutch plate 41 to engage the saw 39 with the end of the block. After the saw has cut through the block, leaving thus a substantially flat surface, the clutch plate 43 is disengaged from the clutch plate 41 and the saw moved in a reverse direction by manually rotating the sleeve 18, by a handle 90 keyed to the left end of the shaft 17, to raise the lapping disc 31 above the quartz block 60. The block may then be advanced by rotating the rod 82 as may be required to engage the block with the lapping disc 31 as it is moved downward when the clutch plate 43 is again engaged in driving relation with the clutch plate 41. The sawed face of the quartz block is then lapped to provide a suitable plane surface for optical inspection. In the next, and succeeding cycles of operation, slabs of quartz are cut from the block having one side thereof lapped, thus avoiding the necessity of transferring the slabs to a lapping apparatus to obtain a suitable plane surface.

While but one form of this apparatus has been shown and described, it will be understood that

many changes and modifications may be made therein without departing from the spirit and scope of the present invention which is limited only by the appended claims.

What is claimed is:

1. An article slabbing and lapping apparatus comprising an article support, a rotatable saw, a rotatable lapping disc, a common rotatable support for the saw and the lapping disc, means for pivoting said rotatable support to engage said saw or disc with an article and for applying a predetermined pressure of engagement, and means operating coaxially of said pivoting means for rotating said saw and said lapping disc.

2. An article slabbing and lapping apparatus comprising an article support, a rotatable saw, a rotatable lapping disc, a common rotatable support for the saw and the lapping disc, means for pivoting said rotatable support to engage said saw or disc with an article, means operating coaxially of said pivoting means for rotating said saw and said lapping disc, and means for applying a predetermined pressure of engagement.

3. An article slabbing and lapping apparatus comprising an article support, a rotatable saw, a rotatable lapping disc, a common rotatable support for the saw and the lapping disc, means for pivoting said rotatable support to engage said saw or disc with an article, and for applying a predetermined pressure of engagement, means operating coaxially of said pivoting means for rotating said saw and said lapping disc, said saw and said disc operating in substantially the same plane, and means for advancing an article with respect to said operating plane.

4. An article slabbing and lapping apparatus comprising a rotatable support, a pair of arms attached to said support, a saw rotatably mounted on one of said arms, a lapping disc rotatably mounted on the other of said arms, means for rotating said saw and said disc, and means operating coaxially of said saw and disc rotating means for rotating said support to engage the saw or lapping disc with an article with a predetermined pressure of engagement.

5. An article slabbing and lapping apparatus comprising a rotatable support, a pair of arms attached to said support, a saw rotatably mounted on one of said arms, a lapping disc rotatably mounted on the other of said arms, a double pulley rotatably mounted on said support, a belt connecting said pulley to said saw and lapping disc, means for rotating said pulley to cause said belt to rotate said saw and said lapping disc, and means for rotating said support to engage the saw or lapping disc with an article.

6. An article slabbing and lapping apparatus comprising a rotatable support, a pair of arms attached to said support, a saw rotatably mounted on one of said arms, a lapping disc rotatably mounted on the other of said arms, means for rotating said saw and said disc, means operating coaxially of said rotating means for rotating said support to engage the saw or lapping disc with an article with a predetermined pressure of engage-

ment, means for supporting an article adjacent said saw and said lapping disc, and means associated therewith for advancing an article with respect to said saw and said lapping disc.

5 7. An apparatus for successively sawing and lapsing a quartz crystal block comprising a pivotable support for a crystal block, means on said support for moving a crystal block relatively thereto, a rotatable member adjacent said support, a pair of arms attached to said rotatable member, a saw rotatably mounted on one of said arms, a lapping disc rotatably mounted on the other of said arms, means for rotating said disc and said saw, and means operating coaxially of said saw and disc rotating means for rotating said rotatable support to engage said saw and said lapping disc with the crystal block with a predetermined pressure of engagement.

10 8. An apparatus for slabbing and lapsing quartz crystals comprising a rotatable saw, a rotatable lapping disc, a common support for said saw and said lapping disc, means for rotating said saw and said disc, means operating coaxially of said rotating means for simultaneously advancing said saw and said lapping disc in a substantially arcuate path, and for engaging said saw and said disc with a crystal with a predetermined pressure of engagement, said saw and said lapping disc advancing about the same axis, a platform for supporting a quartz crystal, and means associated with said platform for moving said crystal into position to be worked upon.

15 9. An apparatus for slabbing and lapsing quartz crystals comprising a rotatable saw, a rotatable lapping disc, a common support for said saw and said lapping disc, means for rotating said saw and said disc, means operating coaxially of said rotating means for simultaneously advancing said saw and said lapping disc in a substantially arcuate path, and for engaging said saw and disc with a crystal with a predetermined pressure of engagement, said saw and said lapping disc advancing about the same axis, a platform for supporting a quartz crystal, and means associated with said platform for moving a portion of said crystal beyond the edge of said platform and into the path of said saw and said lapping disc.

20 10. A cutting apparatus comprising a rotary cutting element, a pivotally mounted arm for rotatably supporting said element, means operating coaxially with the pivot of said arm for driving said cutting element, and means coaxial with said driving means for constantly urging said cutting element against the work.

25 11. A cutting apparatus comprising a rotary cutting element, a pivotally mounted arm for rotatably supporting said element, means operating coaxially with the pivot of said arm for driving said cutting element, means coaxial with said driving means for constantly urging said cutting element against the work including a constantly driven shaft, and friction means interposed between said shaft and the saw supporting arm.

CECIL C. McCAIN.
